UNITED STATES PATENT OFFICE

2,048,517

TELEVISION SYSTEM

Harry P. Pratt, Chicago, Ill.

Application August 5, 1935, Serial No. 34,697

9 Claims. (Cl. 178—6)

The present invention relates in general to television systems and more particularly to providing a novel form of receiving device.

One of the objects of my invention is to provide a novel method of securing variable light control at the receiving end.

Another object is to provide a method by which the intensity of light can be readily controlled in response to impulses received from the transformer.

Another object is to provide a novel method of selecting the color of the light desired and controlling it.

Still another object is to provide means for moving a light over a surface so as to produce an image.

There are other objects of my invention, which together with the foregoing will be described in the detailed specification that is to follow, taken in conjunction with the accompanying drawing.

Briefly, I provide an evacuated container having a cathode therein with means for concentrating the cathode beam and controlling its intensity. The cathode beam is directed upon a crystal which may or may not be in the form of a prism. Various types of crystals may be employed such as the piezo-electric crystal, or any other form of crystal such as one manufactured from quartz. The intensity of the electron emission from the cathode is controlled by a grid.

This application is a continuation in part of my application, Serial No. 628,962.

In the drawing:

Fig. 1 is a diagrammatic view of an embodiment of my invention suitable for television work.

Fig. 2 is a fragmentary showing of a modification thereof showing means for moving the light beam.

Fig. 3 is a cross section of Fig. 2 taken along the line 3—3 looking in the direction of the arrows.

Referring now to the drawing:

The reference character 4 represents a transformer of the usual type having a primary 5 which may be connected through the usual instrumentalities to a radio receiving circuit carrying the light impulses. The secondary winding 6 of the transformer 4 has one terminal connected to a grid or control electrode 7 in an evacuated container 8 which may be constructed of glass or other suitable material. The evacuated chamber 8 has a cathode 9 mounted therein surrounded by a reflecting electrode 10 having somewhat the shape of a parabolic reflector, and is adapted to focus the cathode beam upon an opening in a

tubular anode 11 which is supported by an insulating support 12, which may be of mica or other suitable material. The filament 9 of the tube is connected through a variable resistor 13 to a battery 14 so that the amount of electrical energy flowing through the cathode can be controlled. One terminal of the secondary transformer 4 is connected to the filament. The reflecting electrode 10 may be constructed of any suitable material and is connected through a 10 biasing battery 15 to the filament. The tubular anode 11 is also connected through a battery 16 to the cathode 9, whereby a potential is created between the cathode and anode. A crystal 17 of quartz, or other suitable material is positioned 15 within the tube in front of the tubular anode 11 and is suitably mounted in place so that the electron beam passing through the tubular anode will strike the crystal 17. The crystal 17 may be in the form of a prism if desired. I have found 20 a quartz crystal to be quite satisfactory. A screen 18 is suitably mounted in the end of the tube. Of course, the screen 18 may be mounted without the tube at some convenient point, if desired.

The tube of Fig. 1 is designed for translating 25 electrical impulses into light, and the intensity of the light is controlled by the intensity of the impulse. If we consider its operation in its simplest form, it will be simply that of a translating device. 30

In operation, the electron stream coming from the cathode 9 is projected by the reflecting electrode 10 and by the potential created by the battery 16 upon the tubular anode 9, the reflecting electrode 10 serving to concentrate the beam upon 35 the opening in the tubular anode. As the grid 7 is interposed between the cathode and the anode, the potential obtained from the space charge will inhibit the flow of electrons toward the anode 11. However, in response to the incoming signal, 40 the space charge upon the grid 7 changes in accordance with the intensity of the impulse, thereby producing a change in the number of electrons forming the beam, extending through the tubular anode 11. The electron stream strikes the 45 crystal 17 and by the action of this crystal, a light ray is produced, having an intensity which varies in accordance with the intensity of an electron beam. If the crystal 17 is constructed in the form of a prism, the light emitted therefrom and 50 reflecting upon the screen 18 will be broken up into various colors so that the full spectrum will be obtained. However, by varying the frequency of the incoming signal, any one of the light colors of the spectrum can be selected so that one color 55

is emitted in response to the activation of the crystal by the cathode beam. This selection is determined by the frequency of the incoming signal superimposed upon the beam. Obviously, of course, the screen 18 might be mounted outside the tube and a series of lenses interposed therebetween, if it is desired to concentrate the light beam.

Should this type of device be used in a television receiving system, a light of varying intensity emitted by the crystal 17 can be passed through the usual scanning device to build up a picture in any desired manner.

In Figs. 2 and 3, I have shown a modification of my invention in which a scanning device is not necessary even when this type of tube is used with present day television systems. This result is accomplished by mounting a pair of deflecting plates 19 and 20 within the tube between the anode 11 and the crystal 21. In this instance, I have shown the crystal 21 in 2 units so that white light only is emitted therefrom. Obviously, of course, a prismatic type of crystal could be employed so as to secure color as shown in Fig. 1.

In addition to the deflecting plates 19 and 20 a pair of coils 22 and 23 mounted either within or without the tube can be employed. These deflecting coils are connected together and thence to a low frequency oscillator which generates an oscillating current in the neighborhood say from 30 to 60 cycles. The deflecting plates are connected to another oscillator which generates an oscillating current of high frequency. The deflecting plates will deflect the cathode beam after it passes through the tubular anode in an up and down direction while the coils 22 serve to cause the beam to move over an area. The cathode beam is thus caused to move over the area of the crystal 21. The excitation of the crystal 40 converts the cathode stream into light rays of an intensity proportional to the incoming signal. This light beam however, is caused to cover the area on the screen 18 and reproduce the picture thereon by reason of the deflections occurring in the cathode beam.

The crystals 17 and 21 act as translating devices for converting the cathode beams into light beams. It is relatively difficult to cause a light beam to traverse an area except mechanically, whereas the electron beam, or cathode stream may be deflected readily magnetically or electrostatically. Of course, in the modification shown in Figs. 2 and 3, the screen 18 may obviously be mounted outside of the tube.

While I have illustrated and described certain specific embodiments of my invention, I am aware it may be variously changed and modified without departing from the spirit and scope thereof as set forth in the appended claims.

I claim:

1. In an electronic device, a cathode, an anode, a control electrode interposed between said cathode and anode, a crystal mounted on the other side of said anode, and a screen mounted within said device beyond said crystal.

2. In a thermionic device, a cathode at one end of said device and a tubular anode adapted to cooperate to form an electron stream and a crystal mounted in the path of said stream and a screen mounted at the other end of said device.

3. In a thermionic device, a cathode at one end of said device and a tubular anode adapted to cooperate to form an electron stream and a prismatic crystal mounted in the path of said stream and a screen mounted at the other end of said device.

4. In a thermionic device, a cathode at one end of said device and a tubular anode, adapted to cooperate to form an electron stream and a piezo electric crystal mounted in the path of said stream and a screen mounted at the other end of said device.

5. In a thermionic device, a cathode at one end of said device and a tubular anode adapted to cooperate to form an electron stream, a control electrode for controlling said stream, and a crystal mounted in the path of said stream and a screen mounted at the other end of said device.

6. In a thermionic device, a cathode at one end of said device and a tubular anode adapted to cooperate to form an electron stream, a control electrode for controlling said stream, a crystal mounted in the path of said stream and a screen mounted at the other end of said device and means for creating an electrical field between said anode and crystal.

7. A cathode ray tube having a cathode, an anode and a screen, and a crystal mounted between said anode and screen.

8. A cathode ray tube having a cathode, an anode and a screen, and a quartz crystal mounted between said anode and screen.

9. In a television system, an electron tube housing a cathode, an anode, control electrode, and a screen, means for scanning the area of the screen, and a crystal mounted in the path of the electron beam between the screen and said anode.

HARRY P. PRATT.
